ATTORNEYS.

UNITED STATES PATENT OFFICE

2,075,457

WINDING DEVICE

Norman H. Nye, Cuyahoga Falls, Ohio, assignor
to The Vaughn Machinery Company, Cuyahoga
Falls, Ohio, a corporation of Ohio

Original application April 30, 1931, Serial No.
533,893, now Patent No. 2,016,509, dated Octo-
ber 8, 1935. Divided and this application May
28, 1935, Serial No. 23,884

10 Claims. (Cl. 242—25)

This invention relates to winding devices and more particularly to the provision of improved devices of this kind, wherein the strand or strip of material being wound will have either a constant lineal speed or a controlled variable speed.

This application is a division of my original application Serial No. 533,893, filed April 30, 1931, now Patent No. 2,016,509, issued October 8, 1935.

Winding devices have been constructed here-
10 tofore embodying many different forms of gov-
erning mechanisms, whereby the speed of the winding means is regulated in response to the tension or slackness of the material being wound. In the main, these devices have been imprac-
15 tical or unsatisfactory because the governing mechanism requires very careful adjustment to suit the strength of the material, and if the governing mechanism is not correctly adjusted the tension to which the material is subjected will
20 be excessive, or the speed of the winding means will not be correctly regulated. In my winding device, I propose to govern the winding means in such a way that the speed of the latter will be correctly regulated, regardless of variations oc-
25 curring in the tension of the material being wound.

Accordingly, it may be stated that as an ob-
ject of my invention I aim to provide a novel
30 form of winding device, in which the speed of rotation of the spool, or like winding means, will be automatically regulated in response to the lineal speed of the material.

Another object of my invention is to provide a device of the kind mentioned, in which the speed of rotation of the winding means is regu-
35 lated by means actuated in response to a speed differential between a member driven by the material and a member driven from the source of power which actuates the winding means.

Another object of my invention is to provide a device of the kind mentioned, in which the speed of rotation of the winding means is governed by controlling the delivery of power thereto by control means which is responsive to changes in the lineal speed of the material.

A further object of this invention is to provide winding apparatus in which the arbor or spool is driven at variable speeds through a clutch, and wherein the operation of the clutch is controlled by relative traversing movement between cooperating threaded members one of which is driven at a speed substantially proportional to the speed of the strand and the other of which is driven at a substantially constant speed.

Other objects and advantages of this invention will be apparent from the following description when taken in conjunction with the accompanying sheet of drawings, in which,

Fig. 1 is an elevational view, partly in section, 5 of a winding device embodying my invention, and

Fig. 2 is a partial transverse sectional view of the clutch as indicated by line 2—2 of Fig. 1.

In the drawing, to which detailed reference will presently be made, I have shown winding devices 10 in which the speed of rotation of the winding means is regulated by means responsive to the lineal speed of the material, and although in illustrating my invention I have shown only one such device, it will be understood, of course, that the principle of my invention may be embodied 15 in various winding mechanisms including those used in conjunction with machines for drawing wire, or with machines for performing annealing, tinning, enameling or other operations. 20

In Fig. 1 I have represented generally a ma-
chine 10, such as a wire drawing machine, from
which the strand 11 is being delivered for wind-
ing on suitable rotatable winding means, here
shown in the form of a spool 12. As the strand 25 is wound upon the spool, it may be laid or dis-
tributed thereon by means of the distributing
device 13. No detailed description of this de-
vice is believed to be necessary, since any one of
the many available devices of this kind may be 30 used.

The spool 12 is removably mounted upon a suitable arbor or carrier 14 which is secured to the drive shaft 15. This drive shaft is support-
35 ed in suitable bearings 16 mounted in the casing
17, and is adapted to be driven through the clutch
mechanism 18 from any suitable source of pow-
er, such as the electric motor 19. The clutch 18
is of the type known as a slip clutch, and al-
though any suitable clutch construction may be
40 used, the device should be such that the power
transmitted to the spool through the belt 20 and
the pulley 21 may be readily controlled so as
to regulate the speed at which the spool is ro-
45 tated.

The clutch construction herein illustrated in-
cludes a clutch element or hub 22 keyed to the
shaft 15 and having a plurality of spaced friction
disks 23 carried thereon, and a second clutch ele-
50 ment or drum 24 also having a plurality of fric-
tion disks 25 carried thereon and arranged be-
tween, and in alternate relation with, the fric-
tion disks 23. The clutch element 24 is construct-
ed with a sleeve portion 26 which is journaled 55

upon the shaft 15 and to which the pulley 21 is keyed or otherwise secured. The power transmitted through the clutch is regulated by varying the friction between the sets of friction discs, 5 and for this purpose I provide a disc compressing member 28. This compressing member may be rotatable with the shaft 15 but is supported thereon so as to have limited axial movement thereof. An actuating rod 29 is slidably mounted 10 in the shaft 15, having its inner end operably connected with the compressing member 28 by means of the pin 28', and at its outer end being provided with a rotatable contact button 30.

It will be seen from the arrangement of clutch 15 structure just described that when a force is applied to the button 30 to press the same inwardly toward the spool 12, the friction between the clutch discs is increased, causing a decrease in the amount of slippage therebetween and correspondingly increasing the speed of rotation of the spool. When pressure upon the button 30 is reduced or released, the friction between the clutch discs is also reduced, with the result that the amount of slippage between these discs is increased and the speed of rotation of the spool is correspondingly decreased.

It should be stated that as the driving motor 19 I may employ an electric motor having a substantially constant speed characteristic and 30 which may be mounted as shown in Patent No. 1,990,834, granted February 19, 1935, and vary the speed of rotation of the spool 12 by varying the transmission of power thereto. That is to say, I would permit the motor 19 to be operated 35 at substantially constant speed and vary the speed of the spool 12 by regulating the amount of power transmitted thereto from the motor. Instead of providing a separate motor for driving the spool as shown in Fig. 1, the spool may be 40 driven in the same way from the driving means of the machine 10, which operates at substantially constant speed.

Accordingly, to regulate the speed at which the spool 12 is driven by varying the amount of power 45 transmitted through the clutch, as just explained, I provide means for actuating the clutch in response to the lineal speed of the material being wound. To this end I employ a sheave or drum 32, which is secured to a shaft or spindle 33 and 50 around which the strand 11 is wrapped. This shaft is rotatably mounted in, and extends through a second shaft 34 which is rotatably supported in bearings 35 mounted in suitable supporting means, such as the bearing bracket 36 55 secured to the casing of the machine 10. At the end of the spindle 33 opposite that to which the drum 32 is secured, I provide a helically threaded screw portion 37 which cooperates with a similarly threaded nut 38. This nut is secured to a 60 pulley 39, which in turn is secured to the shaft 34 and is adapted to be driven by any suitable means, preferably by some means operating at substantially constant speed, which might be an individual motor or a part of the machine 10. 65 In this instance the pulley 39 is shown as being driven from the motor 19 by the belt 39'.

It will be seen from this arrangement that, as the strand 11 is taken up by the spool 12, the drum 32 and the spindle 33 to which it is secured 70 will be rotated at a speed corresponding with the rate at which the strand is being wound. At the same time, the pulley 39 and the nut 38 secured thereto will be rotated in the same direction by the belt 39'. If the speed of rotation of 75 the spindle 33 and that of the nut 38 are exactly

equal, there will be no relative movement therebetween. In other words, if the speeds of these two members are equal, there will be no tendency for the screw portion 37 to travel through the nut in either direction, but if the spool 12 tends to take up the strand at a rate which will give the spindle 33 a faster speed of rotation than the nut 38, the spindle will travel through the nut in a lefthand direction, as seen in Fig. 1. If the spool 12 tends to run too slowly, the spindle 10 33 will travel through the nut 38 in the opposite direction to press the contact button 40 against the contact member 41.

To transmit motion from the speed responsive device just described to the clutch 18 so as to regulate the speed of the spool accordingly, I provide a rod 42 on one end of which the contact member 41 is slidably and rotatably mounted and at its opposite end is pivotally connected to the arm 43 of the bell crank lever 44. Suitable guiding means may be provided for the rod 42, such as the guide bracket 45, which is carried by the casing of the machine 10. A rod 46 connects the arm 47 of the bell crank lever 44 with the arm 48 of a clutch actuating lever 49. The lever 49 is pivotally supported adjacent the clutch 18 by means of the bracket 50, and is provided with an actuating arm or finger 51 which engages the rotatable button 30. It will be seen from the arrangement of linkage just described that when the rod 42 is moved toward the right, as seen in Fig. 1, the clutch pin 29 will be moved inwardly to increase the friction between the clutch discs and thereby increase the speed of rotation of the spool.

Since the transmission of power by the clutch 18 depends upon the pressure applied to the clutch discs rather than the extent of movement of these members, I provide a yielding connection between the member 41 and the rod 42, so that changes transmitted through the linkage to the clutch will be in the nature of relatively slowly acting pressure changes rather than as direct or sudden movements, such as would be transmitted through rigidly connected linkage, 45 and would result in sudden changes in the speed of the spool and probably in breakage of the material being wound. This yielding connection comprises a coil spring 52 having one end in engagement with, and centered upon, the contact member 41 and its other end in engagement with and centered upon, a collar 53. The spring 52 is normally under slight compression so as to always hold the member 41 against the button 40. The collar 53 is pinned or otherwise secured to the rod 42, so that upon movement of the contact member 41, changes occurring in the compression of the spring 52 will be transmitted to this rod and through the linkage to the clutch. Movement of the spindle 33 toward the left, as seen in Fig. 1, or in other words, in a clutch releasing direction, will be limited by the engagement of the button 40 with the nut 38, and movement of the spindle in the opposite, or clutch actuating direction, is limited by the hub 54 of the drum 32 engaging the outer end of the shaft 34.

It will now be readily seen from the winding device disclosed, that by my invention I have provided novel mechanism of this kind in which the speed of the spool, or similar winding means, is regulated in response to a speed differential between cooperating members of a control device. Since one of these cooperating members is driven by the material being wound, it will be seen that 75

the speed of rotation of the spool will be correctly regulated in response to the lineal speed of the material and wholly independently of variations occurring in the tension thereof.

5 While I have illustrated and described the device of my invention in a detailed manner, it should be understood, however, that I do not intend to limit myself to the precise details and arrangements of structure illustrated and described, but regard my invention as including such changes and modifications as do not involve a departure from the spirit of the invention and the scope of the appended claims.

Having thus described my invention, I claim:

15 1. In a device of the character described, the combination of rotatable means upon which material is adapted to be wound, means for transmitting power to said rotatable means to drive the latter, and means for controlling the transmission of power to said rotatable means to thereby regulate the speed of the latter including cooperating screw and nut members, one of said members being actuated by the material, and means for driving the other of said members at substantially constant speed.

20 2. In a device of the character described, the combination of rotatable means upon which material is adapted to be wound, means for transmitting power to said rotatable means to drive the latter, and means for controlling the transmission of power to said rotatable means to regulate the speed of the latter, said control means comprising a rotatable threaded member, means for driving said rotatable threaded member, a 25 second rotatable threaded member driven by the material and cooperating with the first mentioned threaded member, and means actuated in response to the speed differential between said threaded members.

30 3. In a device of the character described, the combination of rotatable means upon which a strand is adapted to be wound, means for transmitting power from a power source to said rotatable means to drive the latter, and means for controlling the transmission of power to said rotatable means to regulate the speed of the latter, said control means comprising a pair of cooperating rotatable threaded members one of which is driven at a speed substantially proportional to the speed of the strand, and means actuated in response to relative traversing movement of the threaded members.

35 4. In a device of the character described, the combination of rotatable means upon which a strand is adapted to be wound, means for transmitting power from a power source to said rotatable means to drive the latter, and means for controlling the transmission of power to said rotatable means to regulate the speed of the latter, said control means comprising a rotatable threaded member driven from said power source, a rotatable threaded member driven by the strand and cooperating with the first threaded member, and means actuated in response to relative traversing movement of the threaded members.

40 5. In a device of the character described, the combination of rotatable means upon which a strand is adapted to be wound, means for supplying a strand to be wound, a source of power for the strand supplying means and said rotatable means, and means controlling the transmission of power to said rotatable means to regulate the speed of the latter comprising cooperating threaded members one of which is driven at a 45 rate substantially proportional to said supplying

means and the other of which is driven at a rate substantially proportional to the speed of the strand.

6. In a device of the character described, the combination of rotatable means upon which a strand is adapted to be wound, means for supplying a strand to be wound, a source of power for the strand supplying means and said rotatable means, means controlling the transmission of power to said rotatable means to regulate the speed of the latter comprising cooperating threaded members one of which is driven at a rate substantially proportional to the speed of the strand, and means actuated in response to relative traversing movement of the threaded members.

10 7. In a device of the character described, the combination of rotatable means upon which a strand is adapted to be wound, means for supplying a strand to be wound, a source of power for the strand supplying means and said rotatable means, a clutch for transmitting power to said rotatable means at a variable rate to 15 vary the speed of the latter, cooperating threaded members one of which is driven at a rate substantially proportional to said supplying means and the other of which is driven at a rate substantially proportional to the speed of the strand, 20 and a clutch operating member actuated in response to relative traversing movement of the threaded members.

25 8. In a device of the character described, the combination of rotatable means upon which a strand is adapted to be wound, means for driving said rotatable means at variable speeds, and means controlling the speed of operation of said rotatable means comprising a pair of cooperating rotatable threaded members, means for driving one of said members at substantially constant speed, means for driving the other member at a speed substantially proportional to the speed of the strand, and means actuated in response to relative traversing movement of the threaded members.

30 9. In a device of the character described, the combination of rotatable means upon which a strand is adapted to be wound, means for driving said rotatable means at variable speeds including a clutch, and means controlling the speed of operation of said rotatable means comprising a pair of cooperating rotatable threaded members, means for driving one of said members at substantially constant speed, means for driving the other member at a speed substantially proportional to the speed of the strand, and means actuated in response to relative traversing movement of the threaded members for operating said clutch.

35 10. In a device of the character described, the combination of rotatable means upon which a strand is adapted to be wound, means for driving said rotatable means at variable speeds including a clutch having members operable with relative slippage therebetween, a pair of cooperating rotatable threaded members, means for driving one of said members at substantially constant speed, means for driving the other member at a speed substantially proportional to the speed of the strand, and means actuated in response to relative traversing movement of said members for varying the clutch slippage to thereby vary the speed of said rotatable means.
